UNITED STATES PATENT OFFICE.

BERNAL H. SHARP, OF WOODLAND, CALIFORNIA.

CREAM AND MILK COOLER.

1,101,340.

Specification of Letters Patent. Patented June 23, 1914.

Application filed March 30, 1914. Serial No. 828,256.

To all whom it may concern:

Be it known that I, BERNAL H. SHARP, a citizen of the United States, residing at Woodland, in the county of Yolo and State 5 of California, have invented certain new and useful Improvements in Cream and Milk Coolers; and I do declare the following to be a full, clear, and exact description of the invention, such as will enable others skilled 10 in the art to which it appertains to make and use the same.

This invention relates to new and useful improvements in cooling devices and more particularly to a cream and milk cooler 15 and the primary object of the invention is to provide a simple and efficient device of this character which will thoroughly cool a liquid as the same is passed therethrough.

A further object of the invention resides 20 in providing an improved structure wherein in a water or other cooling circulating means is provided therein for thoroughly cooling the liquid at all points over which the latter flows through the device.

25 A further object of the invention resides in providing a device which is sanitary in every respect and capable of being thoroughly cleaned with little or no difficulty, and still another object resides in providing 30 a device which is simple and durable in construction and extremely inexpensive to manufacture.

With these and other objects in view, the 35 invention consists in the novel features of construction, combination and arrangement of parts, as will be hereinafter referred to and more particularly pointed out in the specification and claims.

In the accompanying drawings forming a 40 part of this application: Figure 1 is a side elevation of a device constructed in accordance with my invention; Fig. 2 is an enlarged vertical section through the device; Fig. 3 is a plan view thereof with the top 45 and strainer removed; and Fig. 4 is a horizontal section as seen on line 4—4 Fig. 2.

In describing the invention, I shall refer 50 to the drawing in which similar reference characters designate corresponding parts throughout the several views, and in which 1 indicates a hollow body of inverted frusto-conical design, the bottom of which terminates in a neck indicated as 2. The walls of this frusto-conical body are hollow, and the 55 top thereof terminates in a flat annular

face 3, the inner peripheral edge of which has an upstanding flange 4 formed thereon. Arranged in the upper portion of the body is a hollow disk 5 which is somewhat conical in design and has the peripheral 60 edge thereof provided at regular intervals therearound with tubular projections 6. These tubular projections are engaged with the inner peripheral edge of the upper portion of the body 1 and afford communication 65 between the interior of this hollow disk 5 and the space between the hollow walls of the body. The top wall of this hollow disk 5 is corrugated as indicated at 7 and the inner wall of the hollow body 1 is also 70 corrugated as indicated at 8, the purpose of which will be hereinafter and more particularly set forth. The upper termination of this conical disk 7 is disposed in a plane 75 above the plane of the upper edge of the annular flange 4 on the top 1 and formed at this upper termination is a cup-like member 9. The bottom of this cup-like member has the greater portion thereof projecting 80 above the downward sloping upper surface of the disk 7, as is obvious from the particular construction described and this bottom is perforated as indicated at 10. A frusto-conical cover 11 is provided for the device, 85 the same having a depending annular flange 12 thereon, which snugly engages the outer wall of the annular flange 4 on the body 1. The cover 11 is provided with a central opening around which is provided an up-standing collar or flange 13 which snugly 90 fits the upper portion of the cup 9 projecting through the opening in the center of the top 11. The aforesaid cup member 9 is adapted to receive the liquid, such as milk and cream, to be passed through the body 95 of the device, and I have provided a strainer for use in connection with this cup member. This strainer comprises an inverted conical member 14 which is hollow and has a depending neck portion 15 thereon fitting 100 snugly within the cup member 9. A cloth or other straining material 16 is adapted to be applied over the upper open end of the member 14 and a rim or band 17 applied to the member to secure the cloth in position 105 thereon. This completes the strainer, and it will be seen that the same may be readily applied to use and held in position on the body 1 by merely applying the same to the cup member 9.

As stated above, the hollow walls of the body 1 and the disk 7 afford a water circulating means through the device. The inlet for such water circulation is had through 5 an inlet pipe extension 18 provided in one well of the body 1 which is adapted to connect with a flexible tubular member leading from a source of supply (not shown). Leading through the wall of the member 1 10 adjacent the inlet pipe 18 and extending completely through the hollow body 1 is a restricted tubular member 19, the inner end of which terminates within the interior of the disk 7 adjacent the center thereof immediately below the bottom of the cup member 9. This member 19 forms the outlet pipe for the cooling medium and the outer end thereof may lead to any desired point.

In operation, the device, after being set 20 up as shown in the drawings, is applied to a milk can or other similar receptacle, so that the neck 2 of the body 1 fits within the neck of the receptacle. The inlet pipe 18 is then connected with a source of water supply and 25 after permitting the water to flow through the inlet pipe, it will be seen that a complete circulation of cold water is had through this device. The milk, cream, or other liquid to be cooled is then poured into the body 30 through the strainer and the liquid will flow regularly through the openings onto the corrugated upper surface of the disk 7. This liquid flowing over the disk will be somewhat retarded in its downward flow 35 over this surface in view of the corrugations and as the water is under constant pressure against the upper wall of this disk in the circulation of the water through the device, it will be seen that the cream, milk or other 40 liquid will be cooled as the same passes over this disk. From the disk 7, the liquid drops downwardly onto the corrugated inner wall of the body 1 and is there also retarded in its downward flow, so as to be thoroughly 45 cooled by the water flowing through the walls of this portion of the device. The flow of the liquid through the device will be even, in view of the disposition of the openings 10 in the bottom of the cup member 9 50 and the corrugating of the surfaces of the device, as described and shown, and the liquid will finally empty through the neck 2 into the receptacle. This cooling process will be rapid, and when the liquid empties 55 into the receptacle, the same will be in proper temperature for whatever purpose the same may be desired.

During the operation of the device, it will be seen that no dust, dirt nor extraneous 60 matter may enter the device in view of its peculiar construction, thus making the same entirely sanitary, and whenever it is desired to clean parts of the device, ready access may be had thereto by the removal of the 65 strainer and cover, as appears obvious.

From the foregoing, it will be seen that I have provided a simple, inexpensive and efficient means for carrying out the objects of the invention, and while I have particularly described the elements best adapted to perform the functions set forth; it is obvious that various changes in form, proportion and in the minor details of construction may be resorted to, within the scope of the appended claims, without departing from the 70 spirit or sacrificing any of the principles of the invention.

Having thus described my invention, what I claim is:

1. A cooling device of the class described, comprising an inverted hollow body of conical design and terminating in a depending neck, the walls of said body being hollow, a hollow disk of conical design in the upper portion of said body and having communication with the interior of the walls of said body, means for circulating a cooling medium through the walls of said body and said disk, a cup-like member formed on the upper central portion of said disk and provided with a perforated bottom to form a liquid feeding arrangement for the device.

2. A cooling device of the class described comprising an inverted frusto-conical body of hollow design having the walls thereof also formed hollow, the bottom of said body terminating in a depending neck, a hollow disk of conical design disposed in the upper portion of the body to project thereabove, a plurality of tubular projections formed on the outer periphery of said disks and engaged with the inner wall of the body at the upper end thereof to afford communication between the interior of the disk and the walls of said body, means for circulating a cooling medium through the walls of said body and said disk, the upper surface of said disk and the inner wall of said body being corrugated, a cup-shaped projection formed on the upper central portion of said disk and having a plurality of perforations in portions of the bottom projecting over said disk, and a cover applied to the body having a central opening therein receiving the cup-shaped projection therethrough.

3. A cooling device of the class described comprising an inverted frusto-conical body of hollow design having the walls thereof also formed hollow, the bottom of said body terminating in a neck, a hollow conical disk arranged in the upper portion of the body to project slightly thereabove, the peripheral edge of said disk being arranged in spaced relation to the inner wall of the body, a plurality of outwardly projecting tubular connections formed on the peripheral edge of said disk and engaged with the inner wall of the body at the upper end thereof to afford communication between the interior of the disk and the interior of

the hollow walls of said body, a supply connection applied to the wall of said body to introduce a cooling liquid therein, an outlet pipe extending through the wall of said body and terminating at its inner end in the interior of the disk at the upper central portion thereof, and a cup-shaped projection formed on the upper central portion of said conical disk having a plurality of perforations in portions of the bottom thereof to

provide means for feeding the liquid to the device.

In testimony whereof I have hereunto set my hand in presence of two subscribing witnesses.

BERNAL H. SHARP.
